UNITED STATES PATENT OFFICE.

FREDERICK A. ROEDER, OF CINCINNATI, OHIO, FRANK DAVIS ADMINISTRATOR OF SAID FREDERICK A. ROEDER, DECEASED, ASSIGNOR, BY MESNE ASSIGNMENTS, TO THE UNITED STATES TORSION BALANCE AND SCALE COMPANY, OF JERSEY CITY, N. J.

TORSIONAL PIVOT-BALANCE.

SPECIFICATION forming part of Letters Patent No. 340,007, dated April 13, 1886.

Application filed May 26, 1884. Serial No. 132,724. (No model.)

To all whom it may concern:

Be it known that I, FREDERICK A. ROEDER, a citizen of the United States, residing at Cincinnati, Ohio, have invented new and useful 5 Improvements in Torsional Pivot-Balances, of which the following is a specification.

My invention relates to that class of balances in which elastic supports are employed for the pivotal bearings of the scale-beams acting torsionally; and it consists in a balance combining with the principle of torsional resistance for such bearings that of tensile resistance, in such relation that both resistances coact to produce the desired result. This may be accomplished 15 by substituting for the ordinary pivot, in which the material is disposed concentrically with the axis of torsion, pivots in which the material is disposed eccentrically thereto in a common plane—as, for example, a flat band or ribbon either homogeneous or composed of duplicate wires or strips arranged in a common plane, preferably at right angles or “edge-wise” to the beam.

My invention also contemplates certain improvements in details of construction, securing ready adjustability of the pivots to the beams, all as more fully hereinafter set forth.

I have exhibited in the drawings, in illustration of my invention, the application of the 25 improvements to a double-beam scale, such as ordinarily employed by druggists, grocers, &c.

Referring now to the drawings, Figure 1 is a perspective view of the double-beam scale, showing a pivot composed of two cylindrical 35 wires or of strips arranged in a plane at right angles or edge-wise to the beam; and Fig. 2 an enlarged detail of the adjusting collars, and a homogeneous ribbon of metal or band employed as the pivot.

40 In the drawings, B B designate the scale-beams, which may be metallic bars or tubes, screw-threaded from one end to a point somewhat beyond the center, and similarly threaded from the other end for a short distance toward 45 the center, as shown, for the reception and adjustment of threaded nuts or collars c, between which the pivotal wires or band w are secured and adjusted in relation to the beams. The

central pivotal support of each beam may be a group of wires or of strips, w, arranged horizontally in a common vertical plane, passing over or through two side posts, a a, which are braced apart by diagonal struts a' a'; or a homogeneous band or ribbon of metal, w, similarly arranged, may be substituted for the wires and 50 clamped between the collars c c, securing the same to the beams. There being one pivot for each beam, the two pivots are arranged in a common vertical plane in parallel lines spaced apart sufficiently to accommodate the beams, 55 and secured in vertical slits in the side posts. Where duplicated wires or strips are employed, a single wire strip passed across and around the side supports two or more times will suffice, being suitably stretched in the process of securing. If homogeneous bands are used, they may be held by pins inserted from 60 side to side through the slits of the posts, or otherwise held in any suitable manner. The beams B are connected at the ends by frames 70 consisting of vertical pieces b, held apart by diagonal struts e, arranged substantially as described for the central frame, but constructed of lighter material, and provided with pivots, such as described, stretched across and retained between the end pieces, and united with 75 the beams at or near the ends of the latter by collars or clamps c, as shown. The scale is provided with a central standard, A, united with the lower beam by means of bifurcated 80 arms, and carrying the poise-weight p, whose function in counterbalancing the combined tensile and torsional resistance of the pivots is the same as where torsional resistance only is involved, and with supporting-standards d d 85 for the scale-pans D rising from the terminal frames.

In Fig. 1 two ordinary cylindrical wires are shown as the pivotal support of each beam, and in Fig. 2 a homogeneous band or ribbon of 90 metal. It will be apparent that as the material of the pivots is arranged eccentrically to the axis of torsion—that is, at the sides thereof in a common plane—in either case the deflection of the beam from the normally-horizontal position of rest involves both a tor- 95

sional and a tensile deflection of the pivots and consequent torsional and tensile resistances, and that these coact in the ordinary operations of the scale. It will be also obvious that 5 the feature of the adjustable collar may be used independently with the ordinary single cylindrical wire pivots of torsion-scales; also, that other substances than metal may be used for the pivots, provided they possess the req-
10 uisite qualities of elasticity and strength.

The band or its equivalent, herein described, may be used for the central beam support in connection with the ordinary single wire em-
ployed for the terminal pendants.

15 I claim as my invention and desire to se-
cure by Letters Patent of the United States—

1. In a torsional balance, a pivot the mate-
rial of which is disposed at the sides of and

approximately in a common plane with the axis of torsion, substantially as set forth. 20

2. A weighing-scale constructed with flat torsion strip or strips stretched horizontally and set up edgewise, substantially as and for the purpose specified.

3. In torsional pivot-balances, a beam pro- 25
vided with adjustable collars arranged to clamp and secure the beam to the pivots, sub-
stantially as and for the purpose set forth.

In testimony whereof I have hereunto set my hand in the presence of two subscribing 30
witnesses.

FREDERICK A. ROEDER.
